United States Patent Office

Des. 218,706
Patented Sept. 15, 1970

218,706

INSTRUMENT FRONT MOUNTING PLATE

Anthony J. DiPinto, 301 Commonwealth Ave.,
Claymont, Del. 19703

Filed Mar. 10, 1969, Ser. No. 16,138

Term of patent 14 years

Int. Cl. D10—08

U.S. Cl. D52—6

FIG. 1

FIG. 2

FIG. 1 is a front perspective view of an instrument front mounting plate, showing my new design;

FIG. 2 is a top plan view thereof;

FIG. 3 is a rear perspective view thereof; and

FIG. 4 is a front elevational view thereof.

The portions of the drawings shown in broken lines are depicted for purposes of illustration only.

I claim:

The ornamental design for an instrument front mounting plate, as shown and described.
